(57) **CLAIM**

The ornamental design for a smart photo frame, substantially as shown and described.

DESCRIPTION

FIG. 1 is a top, front and right side perspective view of a smart photo frame, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of a smart photo frame shown in another configuration; and,

FIG. 9 is a partial enlarged view of FIG. 3.

The broken lines in the figures are for the purpose of illustrating portions of the smart photo frame, which form no part of the claimed design. The dash-dot broken lines in the figures are demarcating enlarged areas and form no part of the claimed design.
